R. O. WONES.

MANIFOLD LOCK.

APPLICATION FILED MAR. 25, 1919.

Patented July 1, 1919.

UNITED STATES PATENT OFFICE.

RAYMOND OTTIS WONES, OF MAPLEWOOD, OHIO.

MANIFOLD-LOCK.

1,308,154.

Specification of Letters Patent.

Patented July 1, 1919.

Application filed March 25, 1919. Serial No. 285,013.

To all whom it may concern:

Be it known that I, RAYMOND O. WONES, a citizen of the United States, residing at Maplewood, county of Shelby, and State of Ohio, have invented certain new and useful Improvements in Manifold-Locks, of which the following is a specification.

This invention relates generally to devices adapted to be applied to automobiles or motor vehicles generally to prevent operation of the engine during the absence of the driver or owner, the invention having more particular reference to a device adapted to be applied to the engine manifold to close and lock the passage therethrough.

The invention has for an object to provide an inexpensive and easily applied and operated device of this kind, and one which may be applied readily to engines of all ordinary types.

For further comprehension of the invention reference will be had to the following description and accompanying drawings, and to the appended claims in which the various novel features of the invention are more particularly set forth.

Figure 1 of the drawings is a face view of the device with one plate removed.

Fig. 2 is a section on the line 2—2 of Fig. 1, showing the device in position.

Fig. 3 is a section on the line 3—3 of Fig. 1.

Fig. 4 is a side view of the device in position on an intake manifold.

Fig. 5 is a view of a split bolt for securing the device to the manifold.

In the drawings the intake manifold of an internal combustion engine such as is used on automobiles and motor vehicles generally is shown at 1 and the carburetor at 2. The manifold has the usual flange 3 on its outer end and the outlet passage 4 of the carburetor the usual flange 5 whereby these parts are ordinarily connected together.

According to my invention I interpose between these flanges a flat and relatively thin casing containing a movable member which may be moved into and out of position closing the intake passage to the engine.

As here shown this casing comprises a pair of plates 10 and 11 of roughly rectangular shape between which is interposed a recessed spacer member 12 in the recess of which the said movable member is located,

the plates 10 and 11 and spacer 12 being suitably united as by the rivets 13 or by suitable screws which are secured in place after insertion of the said member.

The casing thus provided is formed near one corner thereof with an aperture 15 corresponding in size to the manifold passage, and is also provided on opposite sides of this aperture with bolt holes 16 which register with the usual bolt holes in the flanges 3 and 5, the corner of the casing being extended in the form of an ear 17 similar in shape to the corresponding portions of the flanges 3 and 5.

The recess formed in the spacer member between the plates 10 and 11 leads first downwardly from the aperture 15 as at 20 and then horizontally toward the opposite side of the casing as at 21, and then upwardly as at 22 to the outside of the casing.

The locking member is of a thickness to fit easily in this recess and is of approximately similar shape thereto, comprising a vertical portion 27 which is disposed in the recess portion 22 and projects at its outer end through the casing. This projecting end may be provided with a lip or head as indicated at 28 whereby it may conveniently be grasped by the hand.

As shown in the drawings the horizontal portion 21 of the recess in the casing is of considerably greater vertical dimensions than the horizontal portion 26 of the member therein thus permitting vertical movement of the latter whereby the short vertical portion 25 thereof may be moved from the position shown in full lines in Fig. 1 in which the passage to the manifold is unobstructed to that shown in broken lines, in which the passage is closed.

Formed in the vertical portion 27 of the manifold closing member is an opening 30 which is adapted to register with openings 31 and 32 in the plates 10 and 11 when the manifold is closed, with the closing member in the position shown in broken lines. The bow 33 of a padlock 34 may be passed through these openings and the padlock closed thus locking the parts in position closing the passage through the manifold.

To open the manifold it is only necessary to unlock and remove the padlock 34 and push the head 28 inward. When the lock is to be applied the head is pulled outward

until it stops when the openings 30, 31 and 32 will be in registry and the padlock may be applied.

To prevent easy withdrawal of the bolts 5 35 which clamp the casing between the flanges 3 and 5 these bolts may be split and have their ends forced outwardly as at 36 to render more difficult the unscrewing of the nuts 37.

10 As will be apparent this manifold lock may be inserted in a manifold with a minimum of trouble and without the necessity of other work than removing the usual bolts which clamp the carburetor to the manifold.

15 Having thus described my invention and set forth the manner of its construction, what I claim as new and desire to secure by Letters Patent is:—

1. A manifold lock comprising a thin casing having an opening therein adapted to register with the passage through the manifold, a substantially U-shaped member slidably mounted in said casing to move into and out of position closing the manifold pas-

25 sage, said member having a projecting handle portion rigid therewith, and means for locking said member in position closing the manifold passage.

2. A manifold lock comprising a thin casing having an opening therein adapted to register with the passage through the manifold, a member slidably mounted in said casing consisting of parallel portions one of which is adapted to project across the said 30 opening and the other projecting exteriorly to the casing in the form of a handle, a rigid cross piece uniting the ends of said parallel portions, and means whereby said second mentioned parallel portions may be locked to 35 the casing.

3. A manifold lock comprising a thin casing having an opening therein adapted to register with the passage through the manifold, a member slidably mounted in said casing 40 consisting of parallel portions one of which is adapted to project across the said opening and the other projecting exteriorly to the casing in the form of a handle, a rigid cross piece uniting the ends of said parallel portions, said casing and said handle portion being formed with openings adapted to reg-

ister to receive a locking device when the first mentioned parallel portion is closing the said opening into the manifold.

4. A manifold lock comprising a thin casing having an opening therein adapted to register with the passage through the manifold, a rigid member slidably mounted in said casing consisting of parallel portions united at one end by a cross piece, the opposite end of one of said parallel portions being adapted to project across the said opening into the manifold, the opposite end of the other parallel portion projecting from the casing in the form of a handle, said casing having a recess shaped to present parallel portions and a cross portion to receive the respective parts of the said member, said cross portion being widened to accommodate movement of the member into and out of closing position, said casing and said handle portion being formed with openings adapted to register to receive a lock when the member is in closing position.

5. A manifold lock, having an opening 75 therein in register with the passage through the manifold, a substantially U-shaped member longitudinally slidable to cover or uncover said opening, and means for locking said member in position.

6. A manifold lock comprising a casing having an opening therein in register with the passage through the manifold, a substantially U-shaped member slidable therein, a shutter on one end of said member and a handle on the other end thereof, said handle being adapted to be reciprocally moved to cause said shutter to cover or uncover said opening, and means to lock the same in position.

7. A manifold lock having a frame and opening therein to register with the passage through the manifold, a substantially U-shaped member slidable therein, a shutter on one end of said member and a handle on the other end thereof, eyes in said member and in said frame, and locking means for said member adapted to pass through the said eyes.

In testimony whereof I have affixed my 100 signature.

RAYMOND OTTIS WONES.
